UNITED STATES PATENT OFFICE

CHARLES W. RHOADES, OF PERU, INDIANA, ASSIGNOR TO THE PERU ELECTRIC MANUFACTURING COMPANY, OF PERU, INDIANA, A CORPORATION OF INDIANA.

ELECTRIC SAFETY-FUSE.

No. 809,982.

Specification of Letters Patent.

Patented Jan. 16, 1906.

Application filed May 25, 1904. Serial No. 209,812.

To all whom it may concern:

Be it known that I, CHARLES W. RHOADES, a citizen of the United States, residing at Peru, in the county of Miami and State of Indiana, have invented certain new and useful Improvements in Electric Safety - Fuses, of which the following is a specification, reference being had therein to the accompanying drawings, forming part of this specification, in which—

Figure 1 is a plan view of my improved indicating-fuse. Fig. 2 is a longitudinal vertical section on the line II II of Fig. 1. Fig. 3 is a similar view showing the fuse after blowing. Fig. 4 is a plan view of a fuse employing a flat spring. Fig. 5 is a cross-section, enlarged, on the line V V of Fig. 2.

My invention relates to an improvement in the class of electric fuses or cut-outs; and it consists in providing such a fuse with means for indicating its condition immediately upon blowing, consisting of a spring - indicator adapted to be released by the blow and to become erected into view.

Referring to the drawings, 2 is the shell of the fuse, provided with the usual contact ends 3, connected by an interior fuse 4 of suitable resistance for the objects in view and preferably surrounded by a filling 5 of any suitable material. I have discovered that by exerting a lateral tension upon the fuse 4, no matter how slight, the blow will primarily occur at such point and have utilized this phenomenon in my invention, although the ordinary blowing of a fuse will usually operate the device wherever it may occur.

Secured upon the outside of the shell 2 by a screw 5 or other suitable means is a spring-arm 6, made of a coiled wire, as shown in Figs. 1, 2, and 3, or of a flat leaf-spring 6', as in Fig. 4, or of any other suitable form adapted to be drawn down upon the shell under ten-

sion and to spring upwardly therefrom to an erected position when the tension is released. The spring is normally tied down by a thread 45 or wire 7, secured to the spring and passing down through opening 8 in the shell and around the fuse 4, as in Figs. 2 and 5.

Upon blowing, the thread or wire is loosened from the fuse, releasing the spring, which then 50 flies up, as in Fig. 3, carrying with it the thread or wire, so that in this raised position it is readily observed and immediately indicates the blown condition of the fuse.

Various other forms of springs or signal devices may be substituted for the construction shown, or the invention may be varied from in other respects by the skilled mechanic or electrician; but all such changes and variations are to be considered as within the scope 55 of the following claim.

What I claim is—

In an electric fuse, the combination of a cylindrical shell or casing provided with similar terminal circuit-contacts, an inclosed fuse 65 of limited resistance connected with said terminal contacts, an outer spring device secured on the side of the main shell adapted to be bent down against the surface thereof for its full length, a thread device attached to 70 the end of said spring passing through an opening in the shell and looped around the fuse, adapted to retain the spring in a retracted position closely against the shell under tension, and to allow it to rise with the thread device exposing both the spring and thread to view, upon burning of the fuse, substantially as set forth.

In testimony whereof I affix my signature in presence of two witnesses.

CHARLES W. RHOADES.
